(74) Attorney, Agent, or Firm — Rebecca Hanovice;
Michael Catania; Sonia Lari(57) **CLAIM**

The ornamental design for a ball marker, as shown and described.

DESCRIPTION

FIG. 1 is a top perspective view of the ball marker claimed herein;

FIG. 2 is a front elevational view thereof;

FIG. 3 is a rear elevational view thereof;

FIG. 4 is a right side elevational view thereof;

FIG. 5 is a left side elevational thereof;

FIG. 6 is a top plan view thereof; and,

FIG. 7 is a bottom plan view thereof.

The broken lines in the figures show portions of the ball marker that form no part of the claimed design.
